Atty.

Patented Jan. 13, 1925.

UNITED STATES PATENT OFFICE.

HERMANN KUHN, OF CHICAGO, ILLINOIS.

SWIMMING ATTACHMENT.

Application filed March 6, 1924. Serial No. 697,242.

To all whom it may concern:

Be it known that I, HERMANN KUHN, a citizen of Germany, residing at Chicago, in the county of Cook and State of Illinois, have invented certain new and useful Improvements in Swimming Attachments, of which the following is a specification.

This invention relates to certain new and useful improvements in swimming attachments, and more particularly to such attachments as are constructed on the principle of a collapsible web.

The principal object of this invention is to provide a simple, reliable and light attachment that can be easily applied by the swimmer to his wrists and ankles.

Another object of this invention is to provide a swimming attachment, which, while greatly assisting the swimmer in his work, is not cumbersome in any way, and allows the absolute free movement of the hand and foot.

Another object of this invention is to provide a swimming attachment, easily collapsible and of small volume, which the swimmer can easily carry with him.

This above and other objects may be attained by means of the construction illustrated in the accompanying drawing, in which—

Figure 1 is a view illustrating the invention in operation.

Figure 2 is a perspective view of the article.

Figure 3 is a plan view of the article.

Figure 4 is a perspective view of the same showing collapse.

Figure 5 is a detail section of the pivotal connection.

Referring to the drawings, numeral 1 designates a wrist band made out of any suitable material; numeral 2 shows a stiffening ring; numeral 3 designates a rib made out of suitable material; rib 3 has a lug 4 and wire 5 passes through lug 4 and ring 2, at which point rib 3 is pivoted, so as to collapse or open to its extended or operative position; covering or webbing 6 can be made of any suitable material.

In assembling my improved swimming device which comprises the foregoing parts, attention is first directed to the fact that the wrist band 1 is provided with an outstanding flange in which the stiffening ring 2 is arranged and the lugs 4 on the ribs 3 are pivotally connected to the ring at a point adjacent its outer edge, the inner ends of the ribs extending slightly beyond the pivot point. From this, it will be noted that when the ribs 3 are moved to an open position as shown in Figure 2, the extended ends of the ribs will bear against the reinforced portion of the band 1 and limit the outward swinging movement of the ribs. It is preferred to have the connection between the wrist band 1 and the outwardly projecting flange of a flexible nature, whereby when the device is passed forward through the water, the ribs 3 with the covering 6 and reinforced flange of the band 1 will all fold inwardly toward that part of the person to which the device is attached, thus reducing to a minimum the resistance as the device is passed through the water in its folded position.

From the foregoing it is obvious that a swimming attachment made according to the above description, will be of great assistance to the swimmer, in that, while not in any way interfering with the free movement of his hands and feet, it will operate of its own accord, collapsing with each forward movement and opening to its extended or operative position with each backward motion. It is unquestionable that a swimmer using my swimming attachment as above described will avail himself of a much greater forward momentum by the opening of my device, thus securing for himself a larger volume of water pressure and resistance on his backward strokes.

I claim:—

1. A swimming device, including a band of fabric material, an outstanding flange having flexible connection with the band, a reinforcing ring carried by said flange, a plurality of ribs projecting radially from the band, means forming pivotal connection be-

2
tween the ribs and the reinforcing member, and a flexible covering attached to said ribs and extending between the same.

5 2. A swimming device, including a band of fabric material, a flange having flexible connection with the band, a reinforcing ring carried by the flange, a plurality of ribs projecting radially from the band, lugs

on said ribs having pivotal connection with the ring at its outer edge, the inner end 10 of said ribs projecting beyond the pivot points whereby to engage the ring when in an open position, and a webbing attached to and extending between the ribs.

In testimony whereof I affix my signature.

HERMANN KUHN.
